UNITED STATES PATENT OFFICE.

GRACE G. DRAYTON, OF NEW YORK, N. Y.

DESIGN FOR A FIGURE TOY.

52,024.

Specification for Design.

Patented May 7, 1918.

Application filed February 2, 1918. Serial No. 215,206. Term of patent 3½ years.

To all whom it may concern:

Be it known that I, GRACE G. DRAYTON, a citizen of the United States, residing at New York, in the county of New York and State of New York, have invented a new, original, and ornamental Design for a Figure Toy, of which the following is a specification, reference being had to the accompanying drawing, forming part thereof.

I claim:

The ornamental design for a figure toy, as shown.

GRACE G. DRAYTON.
